UNITED STATES PATENT OFFICE.

WILLIAM A. JACKSON AND JOSEPHUS C. CHAMBERS, OF DETROIT, MICH.,
ASSIGNORS TO GEORGE H. LOTHROP, TRUSTEE, OF SAME PLACE.

PROCESS OF NEUTRALIZING INDUCTION.

SPECIFICATION forming part of Letters Patent No. 322,728, dated July 21, 1885.

Application filed February 4, 1885. (No model.)

To all whom it may concern:

Be it known that we, WILLIAM A. JACKSON and JOSEPHUS C. CHAMBERS, of Detroit, in the county of Wayne and State of Michigan, have invented a new and useful Improvement 5 in Process of Neutralizing Induction Disturbances in Telephone-Circuits, of which the following is a specification.

Our invention is a process of neutralizing the 10 disturbing currents generated in a telephone-circuit by induction from external wires, &c.; and it consists in opposing said disturbing currents by induced charges generated by said disturbing currents in one or more insulated 15 bodies, which are good conductors, and are capable of being electrically charged by induction, which will hereinafter be called "inductive bodies," for brevity.

The disturbing currents caused in a telephone-circuit by induction from external objects—such as other wires, the earth, &c.—are generally of higher tension than the normal telephonic currents, and have therefore a much greater tendency to create induced charges in 25 inductive bodies adjacent to the line traversed by such currents than has the telephonic current. We utilize this by placing one or more inductive bodies in electrical proximity to the telephone-circuit, but insulated therefrom, so 30 that an inductive influence will be mutually exerted by said telephone-circuit and the said inductive body upon each other.

In several applications heretofore filed by us for Letters Patent, among which are Nos. 35 133,378, filed May 31, 1884, 140,647, 140,648, and 147,240, we have shown and described several modes of arranging the inductive bodies and circuit, and in the first of said applications described the process which forms the 40 subject of this application. As the several arrangements of mechanism therein shown form the subject-matter of said applications, we do not here claim any particular arrangement of mechanism.

45 In the drawings which we have chosen to herein illustrate some of the arrangements of mechanism which may be used to practice our process, Figure 1 is a vertical longitudinal section in which A represents a bundle of wires, either copper or iron, preferably soft iron, insulated from the line and preferably, though

not necessarily, insulated from each other. L represents the line-wire of the circuit wound in a helix around wires A, and grounded in the usual manner through the telephones at its 55 respective ends. We prefer to place that part of the line which is coiled around the wires A close to the telephone, as it there yields the maximum result.

Fig. 2 is a vertical longitudinal section 60 through an induction-coil, in which P is the primary to be connected with a battery and transmitter in the usual manner; B, the core; N, a spool or bobbin, of wood or iron, in which latter case it may be made integral with B; S, 65 the secondary, and CC, wires of copper or iron, like A, interposed between and insulated from the layers of the secondary.

Fig. 3 is a similar view to Fig. 2, showing 70 the line-wire L, a core or bobbin, B, of either iron or wood, and the insulated wires CC, being a modification of the arrangement shown in Fig. 2, designed for use with a telephone in which the ordinary induction-coil is to be retained, and simply inserted in the circuit, 75 as explained with reference to Fig. 1.

Fig. 4 is an elevation of a partly-made coil, and Fig. 5 a vertical section of a finished coil, which embodies the most satisfactory arrangement devised by us. B represents a core, 80 made of iron, on which are cast or screwed or forged four projecting pole-pieces, b b b b. D represents an insulated wire, either copper or iron, preferably soft iron, wound around the body of the core, and having its ends free, and 85 preferably disconnected, as shown in Fig. 5. P represents the primary, wound over the core B and wire D, and connected with a battery and transmitter in the usual manner, as shown at R and T, Fig. 5. S represents the secondary 90 wound over the primary and connected with the line and ground wires, as shown in Fig. 5. L' represents that end of the line-wire which runs to earth through the receiving-telephone. H represents a helix of insulated wire 95 wound over the secondary, and with its ends preferably disconnected, as shown in Fig. 5. W represents strips of wood at each end of the core, to make a finish to the ends of the coil. This coil is a complete coil, and is designed 100 for use in the transmitter-boxes in place of the ordinary induction-coils usually placed there-

in. This arrangement is illustrated in Fig. 6, wherein T T represent two transmitters at different stations, K K represent two complete induction-coils like those shown in Figs. 2 and 5 5, L represents the line-wire connecting the two stations, and M M represent binding-posts on the transmitters, to which the line-wire is attached.

It is evident that any piece of iron interposed 10 between and insulated from B and the primary will be an electrical equivalent for D.

It will be noticed that in each arrangement of mechanism we place one or more inductive bodies, (represented by A, C, B b, and H,) in 15 electrical proximity to, but insulated from, the circuit or line wire L; and, as these inductive bodies are usually placed in the transmitter-box or near the telephone, they are little exposed to any electrical excitement except 20 that which is caused by electrical currents flowing in the circuit.

When a telephone-circuit is put to use in talking, the receiving-telephone is affected by the normal telephonic current from the sending-station, and also by currents generated in 25 the circuit by induction from other wires and external objects, which cause in the receiving-telephone rattling cracking sounds, often so loud as to drown the sound produced by the 30 telephonic current. When a telephone-circuit through which these two classes of currents are flowing is brought into electrical proximity

to one or more insulated inductive bodies, the said currents tend to cause induced charges in the inductive body or bodies, which, by their inductive reaction on the adjacent convolutions of the circuit, oppose and neutralize to a very great extent the disturbing currents of high tension due to atmospheric and other influences outside of the main line; but by 40 reason of their comparatively low tension this reaction has little effect upon the normal telephonic currents, which flow on into the receiving-telephone.

What we claim as our invention, and desire 45 to secure by Letters Patent, is—

1. The herein-described method or process of neutralizing induction disturbances in a telephone-circuit, consisting in opposing the disturbing currents by induced charges generated by said disturbing currents and reacting upon said disturbing currents. 50

2. The herein-described method or process of neutralizing disturbing currents in a telephone-circuit by establishing an equilibrium 55 between said disturbing currents and electrical charges of opposite polarity inductively generated by said disturbing-currents.

WILLIAM A. JACKSON.
JOSEPHUS C. CHAMBERS.
